(57) **CLAIM**

The ornamental design for a lighting fixture, as shown and described.

DESCRIPTION

FIG. 1 is a perspective view of a lighting fixture showing our design;

FIG. 2 is a side view thereof, opposing sides being mirror images of that shown;

FIG. 3 is a top view thereof;

FIG. 4 is an opposing bottom view thereof;

FIG. 5 is a perspective view of a lighting fixture showing an alternate embodiment of our design;

FIG. 6 is a side view thereof;

FIG. 7 is a top view thereof; and,

FIG. 8 is an opposing bottom view thereof.

The broken lines immediately adjacent to the shaded areas represent the boundaries of the claimed design. Other broken lines are for illustrative purpose only and form no part of the claimed design. None of the broken lines form part of the claimed design.
